UNITED STATES PATENT OFFICE

JAMES R. CLARK, OF ROCHESTER, NEW YORK, ASSIGNOR TO YAWMAN & ERBE MFG. CO., OF ROCHESTER, NEW YORK, A CORPORATION OF NEW YORK

FURNITURE TOP CONSTRUCTION

Application filed November 7, 1928. Serial No. 317,865.

This invention relates to top constructions for filing cabinets, counters, desks and the like for binding the marginal edges of layers of surfacing material such as linoleum.

5 The present invention may be considered as an improvement upon the invention disclosed in my pending application, Serial No. 216,284, filed August 29, 1927.

10 My present invention enables the application of the binding edge construction disclosed in my former application to stock furniture tops which may not have been made or designed particularly for the application of my binding edge construction.

15 A resultant advantage of my improvement is that my binding edge construction may be applied to standard articles of metal furniture or the like without the necessity of the manufacturer altering his dies or other production facilities.

20 The foregoing objects, features and advantages of my invention are set forth in the following description of a specific embodiment thereof as illustrated in the accompanying drawings, wherein:

25 Figure 1 is a perspective of my improved auxiliary furniture top applied to a filing cabinet;

Figure 2 is a detail enlarged section taken 30 along the lines 2—2 of Figure 1;

Figure 3 is a top plan of a battery of three cabinets showing the method of applying the binding strip;

Figure 4 is a detail of said binding strip; 35 and

Figure 5 is a detail section along the lines 5—5 of Figure 3 showing the means for aligning the cabinets in the battery.

40 As exemplary of an article of steel furniture to which the binding edge construction of my invention may be adopted according to my present invention, I have indicated in Figure 1 a metal filing cabinet 10, having the usual drawers 11 and flat top 12.

45 To this I have applied an auxiliary top plate 13 superposed thereon and coextensive therewith and secured thereto by spot welding through the top 12, the auxiliary plate 13 and spacing strips 14 and 15 therebetween.

50 The spacing strips 14 and 15 follow the per-

imeter of the top a spaced distance back from the marginal edge thereof. If the top is of such area in proportion to its thickness as to be likely to make the auxiliary top 13 springy, one or more centrally located spacers 14' may 55 be employed. Suitable surfacing material 17—a sheet of linoleum, for example—may at the time of manufacture, or any desired time subsequently, be laid upon the auxiliary top plate 13 preferably being secured thereto by 60 the usual cement. The linoleum 17 is trimmed to the size of the top it is to cover, and for this purpose the marginal edges of the auxiliary plate 13 may conveniently be 65 used as a trimming guide. For protecting and trimming the edges of the linoleum, I use a binding strip 16 of L or J shaped cross section comprising a horizontal flange 18 frictionally held in the marginal slot formed by the top 12 and the auxiliary top plate 13, and 70 an upwardly bent vertical flange 19 overlying the edge of the linoleum. Preferably the upper edge of the vertical flange 19 is tapered and bent inwardly as shown in Figure 2 to 75 penetrate the edge of the linoleum below its upper surface. This aids in preventing the lifting of the linoleum, the accidental catching of the upper edge of the binding strip which might pull it out of its slot, and the entering of dirt or foreign matter between the 80 edge of the linoleum and the binding strip.

When it is desired to mount several cabinets side by side, a flat strip 20 may be inserted between top bases 12 and 12' and top plates 13 and 13' of adjacent cabinets as 85 shown in Figures 3 and 5. Thus the same means which frictionally engages the binding strip aids in locking the cabinets together and holding their respective top plates in aligned position.

90 A single strip of linoleum 17 may be placed on the entire battery as shown in Figure 3. It may be glued thereto and its edges trimmed, and its edges may then be protected by inserting binding strips 16 around the periphery as illustrated in Figure 3. The horizontal portion of the binding strip may be provided with notches 21 so that the strip 95 may be continuously applied around corners. 100

By means of my present improvement, I may provide any ordinary piece of metal furniture with the requisite marginal slots for receiving my frictionally retained binding strip. And this marginal slot may, by the present improvement, be applied either at the time of manufacture or at any subsequent time and by the manufacturer or by a service man (especially if countersunk rivets be substituted for spot welding). Having provided the top with a marginal slot, the application of a layer of covering material and the binding edge therefor is a simple matter. A roll of standard covering material suffices for practically all installations and a standard edge binder may be used for all installations. The application of covering material and the binding strip may readily be done at any time by the manufacturer, by the dealer or by the purchaser.

While I have described in detail a preferred embodiment of my invention, it is understood that I am not limited to said details except as defined by the following claims.

25 I claim:

1. An article of furniture comprising a top base, a top plate, spacing means between said base and said plate forming a marginal recess therebetween, said means securing said base to said plate, a surface material on said top plate and an edge binder for protecting the edges of said surface material, said edge binder having a horizontal portion, whereby it is held in position by frictional engagement 35 between the marginal edges of the top base and top plate respectively.

2. The combination with an article of metal furniture having a flat top of means for forming a marginal recess about the perimeter of the top for receiving and frictionally retaining a horizontal flange of the binding edge strip, said recess forming means comprising an auxiliary top plate superimposed upon and substantially coextensive 40 with the top, and spacing means between the top plate and the top.

3. As an article of manufacture, an article of metal furniture or the like comprising a flat top, spacing strips thereon inwardly spaced from the margin of the top, an auxiliary top plate superimposed on the top and substantially coextensive therewith, and spaced from the top by said spacing strips, thereby leaving the horizontally disposed 55 marginal slot between the top and auxiliary top plate, for the purpose described.

4. In combination an article of furniture having a flat top, an auxiliary top plate superposed thereon and coextensive therewith, spacing strips around the perimeter interposed between and fixed to the furniture top and the auxiliary top a spaced distance inwardly from the marginal edge providing a marginal recess having parallel side walls, 60 a surface material on said top plate and an

edge binder for protecting the edges of said surface material, said binder having a horizontal flange frictionally retained within the marginal recess by engagement with its parallel side walls.

5. In a furniture top construction, a top base, a top plate superposed thereon and coextensive therewith, spacing means interposed between and fixed to said base and said plate a distance inwardly of the marginal edges thereof providing a marginal recess having two parallel walls, surfacing material on said top plate and an edge binder therefor having a horizontal flange extending a variable distance in the marginal recess and secured by frictional engagement with the parallel walls thereof.

6. In a furniture top construction, a top base, a top plate superposed thereon and coextensive therewith, spacing means interposed between and fixed to said base and said plate a distance inwardly of the marginal edges thereof providing a marginal recess having two parallel walls, an aligning member having horizontally extending edges extending into the marginal recesses of similar articles of furniture for locking them together and holding their tops in the same horizontal plane, by frictional engagement with the parallel walls of the recesses.

7. In a furniture top construction, a top base, a top plate coextensive therewith, means vertically spacing said top plate from said top base and secured thereto inwardly of the marginal edges for holding said base and said plate in fixed and closely disposed relation forming a marginal recess, a surfacing material on said plate, and an edge binder having a horizontal portion extending a variable distance into the recess and being frictionally held by engagement with said top base and said top plate and a vertical portion engaging the edge of the surface material.

In witness whereof, I hereunto subscribe my name this 20th day of October, 1928:

JAMES R. CLARK.
